(57) **CLAIM**

The ornamental design for a segmented sensor enclosure as shown and described.

DESCRIPTION

FIG. 1 is a front perspective view showing a first segmented sensor enclosure;

FIG. 2 is a front view thereof;

FIG. 3 is a rear view thereof;

FIG. 4 is a right-side view thereof;

FIG. 5 is a left-side view thereof;

FIG. 6 is a top plan view thereof; and,

FIG. 7 is a bottom plan view thereof.

Features shown in broken lines in FIGS. 1-7 show unclaimed features that form no part of the claimed design. Any surface shading forms no part of the claimed design but is utilized to illustrate the surface contours of the segmented sensor enclosure.
